HYDRAULIC PROPELLING UNIT FOR PIPE
CLEANERSKyle Irwin Robinson, Glenshaw, Pa., assignor to
Pittsburgh Pipe Cleaner Company, Pittsburgh,
Pa., a company of Pennsylvania

Application September 8, 1948, Serial No. 48,175

5 Claims. (Cl. 15—104.06)

1

The invention relates generally to propelling units for pipe cleaners, and more particularly to hydraulic propelling units.

One of the problems in the manufacture of propelling units for pipe cleaners is to provide a unit that can adapt itself to the different cross sectional areas that are encountered in a pipe cleaning project. Difficulty has been experienced in providing a propelling unit which can be readily compressed in going from a large pipe section to a smaller pipe section or going around a curve and regain the proper size and shape after it has passed through the smaller pipe section.

The object of the invention is to provide a hydraulic unit for a pipe cleaner which will readily expand and contact to adapt itself to different pipe cross sections while retaining its capacity to hold a sufficient quantity of the propelling liquid to operate it.

Other objects of the invention will be readily understood as the description of the invention proceeds.

The invention accordingly is disclosed in the embodiment thereof shown in the accompanying drawings, and comprises the features of construction, combination of elements and arrangement of parts which will be exemplified in the construction hereinafter set forth and the scope of the application of which will be indicated in the claims.

For a fuller understanding of the nature and objects of the invention, reference should be had to the following detailed description taken in connection with the accompanying drawings, in which:

Figure 1 is a view in perspective of three hydraulic units constructed in accordance with this invention disposed on a stem showing how they may be connected to pipe cleaning members.

Fig. 2 is a view in section showing details of the structure of the hydraulic unit.

Fig. 3 is a view in end elevation of the hydraulic unit,

Figs. 4, 4a, 5 and 5a are composite views showing the vanes employed in the hydraulic unit, both in plan and end elevation,

Fig. 6 is a view in side elevation of a back-up plate employed in the hydraulic unit,

Fig. 7 is a view in plan of the back-up plate shown in Fig. 6,

Fig. 8 is a view in side elevation of the hydraulic unit showing it disposed in a pipe which is illustrated in section,

Fig. 9 is a view in side elevation of a modification of the hydraulic unit,

Fig. 10 is a view in end elevation of the hydraulic unit shown in Fig. 9,

Fig. 11 is a view in plan of a portion of the shell of Fig. 9, the drawing being reduced in size, since it is to illustrate how the plate forming the shell is cut.

Referring now to the drawings and Fig. 1 in

2

particular, the hydraulic unit shown generally at 10 is substantially the shape of a conic frustum to facilitate its introduction into a pipe and enable it to readily travel through pipes of different cross sectional areas and around bends. As illustrated, any predetermined number of hydraulic units may be attached to pipe cleaning members shown generally at 11. The number of hydraulic units employed will depend on the problem at hand.

In Fig. 2, the hydraulic unit shown generally at 10 is disposed on a stem 12. In this instance, the stem 12 is a coil spring which is quite flexible so as to enable the hydraulic units 10 and pipe cleaning members 11 to be propelled or drawn through pipe-sections of different sizes and around bends. However, it will be readily appreciated that many different types of stems well-known in the art may be employed. For example, articulated stems or even stems comprised of straight rigid pipe may be utilized if the pipe to be cleaned does not have sharp bends.

In the preferred embodiment of the invention illustrated in Figs. 2 to 8, inclusive, the hydraulic unit comprises a shell 13 which simulates in shape the outside of a conic frustum. In order to enable the mounting of the shell 13 on the stem 12, two nuts 14 and 15 are provided. These nuts 14 and 15 are provided with internal threads which enable them to be turned onto the stem 12 to dispose them in any predetermined position.

The nuts 14 and 15 are provided with threaded openings for receiving the set screws 16 and 17. The set screws are employed for anchoring the nuts 14 and 15 in predetermined positions on the stem for a purpose which will appear hereinafter.

The size of the shell 13 will depend on the size of the hydraulic unit it is desired to build. One of the advantages of this type of hydraulic unit is that it can be made of any predetermined size to adapt it to pipes of different sizes. The shell can be made of sheet steel or bronze or any metal that will stand up to the rough usage to which it will be subjected. Stainless steel is very satisfactory, since it resists corrosion.

In the preferred embodiment illustrated in Fig. 2, a plurality of short vanes 18, shown in plan and end view in Fig. 5 and a plurality of long vanes 19 illustrated in Fig. 4 are employed. These vanes 50 are preferably made from spring steel or bronze or some other metal that is flexible so that they may be readily bent to enable the hydraulic unit to pass through pipe sections of different cross sectional area. Each vane is provided with a plurality of openings 20.

In order to mount the vanes 18 and 19 on the shell 13, two rows of openings 21 are provided in the shell. These openings are the same size as the openings 20 provided in the vanes. As shown in Fig. 2, only one layer of vanes 18 is provided while two layers of vanes 19 are utilized. In mounting the vanes 18, they are disposed to

overlap one another in the same manner the whole way around the shell 13. The vanes 19 are preferably disposed to overlap one another in one way on the outside and in the opposite manner on the inside. Reference to Fig. 3 shows that the outer layer of vanes 19 as they proceed counterclockwise around the shell extend over the next vane while on the inside proceeding counter-clockwise around the shell each vane extends under the next vane. The reason forlapping the vanes 19 in this manner is based on experience which has revealed that good results have been obtained by arranging the vanes in this manner. However, it is to be understood that a satisfactory hydraulic unit may be produced bylapping the vanes in different arrangements. While one layer of vanes 18 and two layers of vanes 19 have been illustrated, this is a matter of choice to anyone skilled in the art, and any predetermined number of layers may be utilized.

The vanes 18 and 19 are mounted on the shell 13 by the use of short bolts 22. These short bolts extend through the three layers of vanes and the shell 13 as illustrated. There is considerable merit in mounting the vanes in this manner, since if any group of vanes is damaged, it can be removed readily and new vanes substituted. However, it will be readily appreciated that the vanes can be mounted in any other suitable manner well known in the art.

As shown, a back-up plate 23 is disposed in the vanes 19. This back-up plate is generally mounted just beyond the outer end of the shell 13. However, its location will depend on the functioning of the vanes that it is desired to obtain. It will be readily appreciated that the cross section of the pipe that the hydraulic unit will pass through will be determined to some extent by the location and size of the back-up plate 23.

The back-up plate 23 is actually an annular plate, the diameter of the opening in the center being large enough to permit it to be fitted over the stem 12. As shown in Figs. 6 and 7, the nut 24 is mounted on the plate 23. The nut 24 is provided with an internal thread which will fit the stem 12. It is also provided with a set screw 25 for setting it in any predetermined position on the stem 12. The back-up plate is attached to the nut 24. This may be accomplished by welding, as shown at 26, or any other suitable means known in the art.

The hydraulic unit described so far might function under certain conditions, but it has been found that when subjected to water under pressure, it does not hold enough water for efficient operation and the vanes are readily bent under the water pressure and when bent beyond their capacity to recover their original shape, the unit is damaged beyond further use and has to be repaired.

In order to adapt the unit for holding enough water for an efficient operation and to so support the vanes 18 and 19 that they are not distorted beyond recovery, a mass of some suitable resilient material shown generally at 27 is employed and disposed inside of the vanes 19. In this particular embodiment of the invention, three layers 28, 29 and 30 of sponge rubber are employed. The type of sponge rubber selected will depend on the results desired. Anyone skilled in this art can readily select the proper grade of sponge rubber. In selecting the rubber, the porosity

should be such that it will hold substantially all water applied to it under pressure. In the rubber available generally, there will be a certain amount of the water that gets through but not enough to affect efficient operation. Further, the sponge rubber should not be too soft. It should have enough resilience to permit the vanes to contract a predetermined amount but sufficient capacity or elastic memory to enable it to regain its original shape and return the vanes to their original positions, as soon as the distorting pressures have been removed.

In the embodiment illustrated, the layers 28, 29 and 30 will be cut to the shape of the vanes as illustrated. The layer 28 will have a larger opening cut in the center than the layers 29 and 30 to accommodate it to the nut 24.

In assembling the structure illustrated in Figs. 2 to 8, inclusive, the nut 14 will first be disposed on the stem 12 and set in a predetermined position by means of the set screw 16. As shown, the nut 14 has the corner cut off one end to give it a shape somewhat similar to a conic frustum to adapt it to receive the shell 13. Next the nut 15 is moved on the stem 12 toward the nut 14. When it abuts against the shell 13, it firmly clamps it in position on the stem. The nut 15 is locked in position by the set screw 17.

The back-up plate is now moved on the stem 12 until it engages the vanes 19. It is then fixed in position on the stem 12 by means of the set screw 25. It will be observed that the shell 13 and the vanes 18 and 19, in effect, form a shell the shape of a conic frustum. The vanes are actually an extension of the shell 13.

The back-up plate 23 fixed on the stem 12 forms a fulcrum about which the vanes 18 and 19 may turn inwardly when distorted in shape as the hydraulic unit is forced through a pipe. The shell 13 supports the vanes 18 and 19 against turning outwardly when subjected to high water pressures to propel the hydraulic unit through a pipe line. The making of the vanes 18 shorter than the vanes 19 adds strength to resist the turning or spreading of the vanes outwardly.

The next step in the assembling of the unit is the mounting of the resilient mass 27 on the trailing side of the back-up plate 23. When the resilient material is discs of sponge rubber, such as illustrated, they may readily be fitted over the stem 12 and fixed in position by cementing or other suitable means known in the art. As pointed out before, the characteristics of the hydraulic unit will be controlled to an appreciable extent by the characteristic of the resilient mass 27 which is employed. Further, the shape and material from which the vanes 18 and 19 are made will also effect the operating characteristics of the unit.

In the modification illustrated in Fig. 9, the supporting shell 31 is shorter than the shell 13 of Fig. 2 and is fixed to the stem 32 directly by means of a set screw 33. The vanes 34 are made by cutting slits 36 in a light weight shell 35, the development of which is shown in Fig. 11. The slits 36 do not extend to the small end of the shell 35.

One edge of each vane formed by cutting slits 36 in the shell 35 is turned in to provide a wall 37. Further, the vanes are arranged to overlap one another. In Fig. 10 progressing counterclockwise each vane overlaps the next vane. In this modification, the overlapping takes place on the side of the vane having the turned-in triangular wall 37.

In order to limit the outward movement of the vanes, openings 38 are provided in each triangular wall 37 near the outer end and through these openings 38 a wire or cable 39 is threaded, and the ends of the wire or cable 39 are connected together at 40 to form a closed loop. This wire or cable will limit the outward movement of the vanes, so that they cannot be distorted beyond their elastic limit. Thus they will always regain their shape. A back-up plate 41 will be employed and disposed inside of the vanes 34 to support a mass of some suitable resilient material, such as sponge rubber 42 disposed in the vanes. The back-up plate 41 and the sponge rubber 42 may be mounted in similar manner to that described for the modifications illustrated in Figs. 2 to 8, inclusive.

In operation, when a hydraulic unit, such as illustrated in Figs. 2 to 8, inclusive, is inserted into a pipe, the vanes 18 and 19 are bent inwardly slightly as shown in Fig. 8. The mass of resilient material, such as the sponge rubber layers 28, 29 and 30, are compressed and extend outwardly, as shown at 56. The distortion of the vanes 18 and 19 may be readily effected, since the overlapping vanes are disposed to slide across one another. If the hydraulic unit moves from a larger pipe section to a smaller pipe section, it may contract more than shown in Fig. 8, the vanes turning about the back-up plate 23. The sponge rubber mass will merely extend further outwardly in the manner shown at 56.

When the hydraulic units move to a larger pipe section, the vanes 18 and 19 because of their own resilience and under pressure of the sponge rubber, will expand and fill the opening. In this manner, the unit will prevent the escape of water under pressure between the pipe and the vanes. Further, the sponge rubber will fill all openings inside of the vanes so as to hold enough water to efficiently operate the unit. It is true that a certain amount of water will escape through the sponge rubber, but if the rubber is properly selected, the amount of water that escapes will not be detrimental to efficient operation.

The modification shown in Figs. 9 to 11 will operate in much the same manner and further description of the operation is not necessary. The modification selected may depend to some extent on the type of work to be done and the amount of money that can be spent in making hydraulic units for the problem at hand.

Since certain changes may be made in the above device, and different embodiments of the invention can be made without departing from the scope thereof, it is intended that all matter contained in the above description or shown in the accompanying drawing shall be interpreted as illustrative and not in a limiting sense.

I claim as my invention:

1. In a hydraulic unit for pipe cleaners, in combination, a stem, a shell substantially the shape of a conic frustum carried by the stem, a plurality of flexible members carried by the shell, an annular plate carried by the stem, the annular plate being disposed in the flexible members to provide a fulcrum about which they may bend to enable the hydraulic unit to adapt itself to pipes of different cross section, and resilient means disposed inside of the flexible members forming the large end of the hydraulic unit and on the trailing side of the annular plate, the resilient means thereby supporting the flexible members.

2. In a hydraulic unit for propelling a pipe

- cleaner, in combination, a stem, a shell simulating the shape of a conic frustum carried by the stem, vanes carried by the shell, the vanes being disposed in substantial alignment with the shell
- 5 to constitute an extension of it, a back-up plate disposed in the vanes to constitute a fulcrum about which they may turn, and a resilient mass disposed inside the vanes and on the trailing side of the back-up plate, the resilient mass serving to support the vanes and to hold water under pressure.
- 10 3. In a hydraulic unit for propelling a pipe cleaner, in combination, a stem, a shell simulating a conic frustum, means for mounting the shell
- 15 on the stem in a predetermined position, vanes carried by the shell, the vanes being disposed in axially stepped relation longitudinally of the shell to give them a predetermined resistance to outward movement and a small resistance to inward
- 20 movement, the vanes also being disposed in overlapping relation circumferentially to facilitate lateral movement relative to one another, and a resilient mass disposed in contact with the vanes to help them regain their normal shape after they
- 25 have been distorted inwardly.
4. A hydraulic unit for propelling a pipe cleaner, in combination, a stem, a shell the shape of a conic frustum carried by the stem, a plurality of layers of vanes disposed in circumferential
- 30 overlapping and axially stepped relation carried by the shell, means disposed in the shell for predetermined line about which they may be distorted inwardly, and a mass of sponge rubber disposed inside the vanes but on the trailing side
- 35 of the back-up plate about which the vanes may be distorted inwardly, said mass of sponge rubber being in contact with the vanes serving to support them as they are distorted inwardly and to hold water that may be applied to the hydraulic
- 40 unit for propelling it through a pipe.
5. In a hydraulic unit for propelling a pipe cleaner through a pipe, in combination, a stem, a member simulating the shell of a conic frustum carried by the stem, the outer end of the shell
- 45 being slit to provide a plurality of vanes, the vanes being shaped to lie in circumferential overlapping relation, and means for limiting the outward movement of said vanes, a back-up plate disposed in the vanes to predetermine the point
- 50 about which they may be distorted inwardly and a mass of sponge rubber disposed inside and in contact with the vanes to support them when
- 55 they are being distorted inwardly and to help them regain their normal position, said mass of sponge rubber being disposed on the trailing side of the back-up plate.

KYLE IRWIN ROBINSON.
